LAMP FIXTURE SUPPORTING DEVICE

Ernst G. Anderson, deceased, late of Chicago, Ill.,
by E. Harold Anderson, administrator, Lake
Bluff, Ill., assignor to Simplet Electric Co.,
Chicago, Ill., a corporation of Illinois

Application July 8, 1946, Serial No. 681,835

6 Claims. (Cl. 248—342)

1

The present invention relates to lamp fixture supporting devices and more particularly to an improved device for adjustably supporting an elongated lamp fixture, such, for example as a fluorescent lamp fixture, from a conduit box or the like.

The advent of fluorescent lighting employing elongated tubular lamps has given rise to the problem of providing an inexpensive and rugged device for supporting an elongated lamp fixture from a ceiling outlet fixture (usually in the form of a conduit box or the like) having an open side facing downwardly. In the usual installation, it is also desirable to provide for adjustment of the position of the lamp fixture in a horizontal plane, thereby to permit angular positioning of the elongated light pattern. While the facilities provided to permit angular adjustment of the lamp fixture should be such as to permit the adjustment to be made without the use of tools, they should not permit free rotation of the fixture since in such event the fixture may be rotated from an established desired position to an undesired position by vibrational or other forces inadvertently imposed thereon.

It is an object of the present invention, therefore, to provide an improved device for supporting an elongated lamp fixture from a conduit box or the like.

It is another object of the invention to provide an improved device of the character described which is so constructed and arranged as to permit angular adjustment of the supported fixture without the use of tools and yet will not permit inadvertent rotation of the fixture after the desired setting thereof is once established.

It is a further object of the invention to provide a device of the character described which is of rugged construction, is comprised solely of a relatively small number of die stampings of low cost and yet is of pleasing appearance.

The invention, both as to its organization and method of operation, together with further objects and advantages thereof, will best be understood by reference to the following specification taken in connection with the accompanying drawings, in which:

Fig. 1 is a perspective view illustrating the present improved supporting device in its use to support a fluorescent lamp fixture;

Fig. 2 is a fragmentary perspective view illustrating certain parts of the present improved supporting device prior to assembly;

Fig. 3 is a side sectional view taken along the lines 3—3 of Fig. 4 illustrating the supporting

2

device shown in Fig. 1 assembled upon a conduit box;

Fig. 4 is a bottom elevational view of the device;

Fig. 5 is a sectional view taken along the lines 5—5 in Fig. 4; and

Fig. 6 is a fragmentary sectional view illustrating a modification of the device.

Referring now to the drawings and more particularly to Fig. 1 thereof, the present improved device, generally identified at 10, is there illustrated in its use to support an elongated fluorescent lamp fixture 11 from a conduit box 12. The conduit box 12 is positioned along a structural ceiling 13 and is fixedly mounted on a structural member 16 by means of screws or bolts 15. As shown, the elongated lamp fixture 11 is provided with eye-bolts 11a and 11b at opposite ends thereof which connect with the end links of chains 14 and 15 extending to the notched ends 27a and 28a, respectively, of the arms 27 and 28 embodied in the device 10. Thus the fixture 11, which may conventionally house one or more elongated and tubular fluorescent lamps, is supported in a horizontal plane displaced downwardly from the ceiling 13. Current for energizing the lamps may be supplied from the conductors of a cord 11c which is plug-connected with the socket connector of the device 10 in a manner fully apparent from the following description.

In brief, the present improved supporting device 10 comprises a base 17 adapted to be fixedly secured to the conduit box 12 and to cover the open lower side thereof; an arm member 18 provided with the oppositely directed arms 27 and 28 and a center portion generally indicated at 29; and means comprising a cup-shaped assembly member 19 coacting with the center portion 29 of the arm member 18 rotatably to support this arm member from the base 17. The device further comprises a socket type circuit connector 20 positioned within and supported by the cup-shaped assembly member 19 and held in assembled position within this member by means of a U-shaped assembly element 21 having laterally extending leg ends which are screw-connected to the base 17 by means of assembly screws 23.

More specifically considered, the base 17 is provided with openings 17a and slots 17b either of which may be used to receive screws 22 which are threaded into struck-out portions 12a of the conduit box 12 fixedly to mount the base upon the conduit box at the open side thereof. The base 17 further includes a die-formed downwardly extending cup-shaped portion 24, the bottom

wall 25 of which is provided with an enlarged opening 26 for receiving the tubular wall of the cup-shaped assembly member 19. This opening is in registry with an enlarged opening 31 formed in the center portion 29 of the arm member 18. The arm member center portion 29 is further provided with an annular part 30 the upper surface of which is in bearing engagement with the wall 25.

In accordance with one feature of the present invention, the cup-shaped assembly member 19 is utilized to clamp the engaged surfaces of the base 17 and the arm member 18 in tight frictional engagement, such that relative rotation therebetween is frictionally resisted to hold the arm member in any angular position to which it may be adjusted relative to the base 17. To this end, the cup-shaped member 19 is provided with an inwardly deformed portion 34, the rim part 34a of which is spun over during assembly of the device to engage the upper side of the wall 25 and tightly clamp the bearing surfaces of the two members 17 and 18 in engagement. For the purpose of limiting rotation of the arm member 28 relative to the base 17 to an angle slightly less than 360°, a stop part 25a is struck downwardly from the wall 25 to project into the rotational path of cooperating stop parts 27c punched outwardly from the arm member center portion 29 adjacent the arm 27. With the described construction, the friction developed at the engaged surfaces of the three parts 17, 18 and 19 serves to prevent relative rotation between the parts 17 and 18 except when a rotational force of appreciable magnitude is positively applied to one or both of the arms 27 and 28 adjacent the ends thereof. Thus inadvertent rotation of the elongated lamp fixture 11 carried by the supporting device 10 from a desired set position is positively prevented.

In accordance with a further feature of the present invention, the ruggedness and weight-supporting capabilities of the device 10 are materially enhanced by angularly relating the arms 27 and 28 to extend outwardly and downwardly along lines which extend substantially straight away from the center portion 29 of the member 18 toward opposite ends of the lamp fixture 11 in the manner best shown in Fig. 1 of the drawings. With this arrangement, the weight of the fixture 11 and the lamps supported thereby produce forces in the arms 27 and 28 which are manifested almost exclusively as tension forces longitudinally of the arms. Thus there is no possibility of the arms being deformed due to imposition of an excessive weight thereon. The strength of the structure is further enhanced by employing arms 27 and 28 of U-shaped or channeled cross-section throughout the major portion of the lengths thereof. At the arm ends, the channel side members are pressed together and slotted as indicated at 27b and 28b to receive the end links of the chains 14 and 15. The appearance of the device is materially enhanced by shaping the center portion 29 of the arm member 18 to have opposed side skirts 32 and 33 which embrace the sides of the cup-shaped portion 24 of the base 17. These skirts also serve to enhance the rigidity of the arm member 18 in that they interconnect the side walls of the channeled arms 27 and 28.

As indicated above, the cup-shaped assembly member 19 is utilized to support the socket type circuit connector 20. To this end, the bottom wall of the member 19 is provided with a rectangu-

larly shaped opening 35 through which a shouldered portion of the rectangular-shaped connector 20 extends to render the outlet contacts of the connector accessible for circuit connection with the lamps of the fixture 11. It will be understood that the shouldered portion of the connector housing seats upon the edges of the opening 35 and that due to the rectangular configuration of this housing and the opening 35 through which the shouldered housing portion projects, the assembly element 21 not only serves to hold the connector 20 in position within the member 19 but to restrain the connector against rotation relative to the member 19.

If desired, the modified construction illustrated in Fig. 6 of the drawings may be employed for the purpose of holding the connector 20 in assembled position within the cup-shaped assembly member 19. As there shown, the U-shaped assembly element 21 is provided with laterally extending leg ends 21a and 21b which are adapted to be snapped beneath the deformed portion 34 of the member 19 during assembly of the device to hold the connector 20 in seating engagement with the bottom wall of the assembly member 19. This construction of the assembly element 21 provides a convenient arrangement for assembling the connector 20 upon the member 19 without using screws, bolts or the like.

From the foregoing explanation, it will be understood that the present invention affords a simple, rugged and reliable device for supporting a fluorescent or other elongated lamp fixture from a conduit box or the like in any desired angular setting within a horizontal plane. In this regard it will be understood that to change the angular position of the fixture 11, it is only necessary to grasp one or both of the arms 27 and 28 adjacent the ends thereof and impose the necessary force thereon to rotate the arm member 18 relative to the base 17. Such relative rotation occurs at the engaged surfaces of the parts 25 and 30. Due to the clamping force exerted upon these bearing surfaces by the assembly member 19, inadvertent rotation of the fixture 11 is positively prevented once the desired lamp fixture setting is established in the manner just explained.

While there have been described what are at present considered to be the preferred embodiments of the invention, it will be understood that various modifications may be made therein which are within the true spirit and scope of the invention as defined in the appended claims.

What is claimed is:

1. A device for supporting an elongated lamp fixture from a conduit box or the like having an open side, comprising a base adapted to be fixedly secured to a conduit box or the like to at least partially cover the open side thereof, an arm member provided with opposed and angularly related rigid arms extending outwardly and downwardly from the center portion thereof and provided with ends adapted for connection with fixture supporting elements, and an assembly member rotatably supporting said arm member from said base member and having portions frictionally engaging said base and said center portion of said arm member and holding said base and said arm member in firm engagement with each other.

2. A device for supporting an elongated lamp fixture from a conduit box or the like having an open side, comprising a base adapted to be fixedly secured to a conduit box or the like to at least partially cover the open side thereof and provided

with a central opening, an arm member provided with oppositely extending rigid arms adapted to have fixture supporting elements attached thereto and having a central opening registering with the central opening of said base, the surfaces of said base and said member adjacent said openings being in engagement, and an assembly member extending within said openings in said base and said arm member and having portions embracing the edges of said openings rotatably to support said member from said base and to clamp said surfaces in frictional engagement, whereby said base and said arm member are frictionally restrained against relative rotation.

3. A device for supporting an elongated lamp fixture from a conduit box or the like having an open side, comprising a base adapted to be fixedly secured to a conduit box or the like to at least partially cover the open side thereof and provided with a central opening, an arm member provided with oppositely extending arms adapted to have fixture supporting elements attached thereto and having a central opening registering with the central opening of said base, the surfaces of said base and said member adjacent said openings being in engagement, a cup-shaped member provided with deformed side walls embracing the edges of said openings rotatably to support said arm member from said base and to clamp said surfaces in frictional engagement, whereby said base and said arm member are frictionally restrained against relative rotation, said cup-shaped member having an opening in the bottom thereof, a circuit connector supported within said cup-shaped member and provided with outlet contacts accessible through said last-named opening, and assembly means holding said connector in assembled position within said cup-shaped member.

4. A device for supporting an elongated lamp fixture from a conduit box or the like having an open side, comprising a base adapted to be fixedly secured to a conduit box or the like to at least partially cover the open side thereof and provided with a central opening, an arm member provided with oppositely extending arms adapted to have fixture supporting elements attached thereto and having a central opening registering with the central opening of said base, the surfaces of said base and said member adjacent said openings being in engagement, a cup-shaped member provided with deformed side walls embracing the edges of said openings rotatably to support said arm member from said base and to clamp said surfaces in frictional engagement, whereby said base and said arm member are frictionally restrained against relative rotation, said cup-shaped member having an opening in the bottom thereof, a circuit connector supported within said cup-shaped member and provided with outlet contacts accessible through said last-named opening, and a U-shaped assembly element embracing said circuit connector and provided with laterally projecting leg ends extending beneath the deformed portions of said cup-shaped member to hold said connector in assembled position within said cup-shaped member.

5. A device for supporting an elongated lamp fixture from a conduit box or the like having an open side, comprising a base adapted to be fixedly secured to a conduit box or the like to

at least partially cover the open side thereof and provided with a central opening, an arm member provided with opposed and angularly related arms extending outwardly and downwardly from the center portion thereof and provided with notched ends adapted for connection with fixture supporting elements, the center portion of said arm member having an opening registering with the central opening of said base and the surfaces of said base and said arm member adjacent said openings being in engagement, a cup-shaped member provided with deformed side walls embracing the edges of said openings rotatably to support said arm member from said base and to clamp said surfaces in frictional engagement, whereby said base and said arm member are frictionally restrained against relative rotation, said cup-shaped member having an opening in the bottom thereof, a circuit connector supported within said cup-shaped member and provided with outlet contacts accessible through said last-named opening, and assembly means holding said connector in assembled position within said cup-shaped member.

6. A device for supporting an elongated lamp fixture from a conduit box or the like having an open side, comprising a base adapted to be fixedly secured to a conduit box or the like to at least partially cover the open side thereof and provided with a central opening, an arm member provided with opposed and angularly related arms of channeled cross-section extending outwardly and downwardly from the center portion thereof in substantially straight lines toward the ends of the supported fixture, said arms being provided with notched ends adapted for connection with fixture supporting elements extending to the ends of the supported fixture, the center portion of said arm member having an opening registering with the central opening of said base and the surfaces of said base and said arm member adjacent said openings being in engagement, a cup-shaped member provided with deformed side walls embracing the edges of said openings rotatably to support said arm member from said base and to clamp said surfaces in frictional engagement, whereby said base and said arm member are frictionally restrained against relative rotation, said cup-shaped member having an opening in the bottom thereof, a circuit connector supported within said cup-shaped member and provided with outlet contacts accessible through said last-named opening, and assembly means holding said connector in assembled position within said cup-shaped member.

E. HAROLD ANDERSON,
Administrator With the Will Annexed of the
Estate of Ernst G. Anderson, Deceased.
